H. M. ROSS

BOTTLE FILLING MACHINE

Filed Sept. 28, 1923

Inventor

Hugh M. Ross

By his Attorneys

Kenyon & Kenyon

UNITED STATES PATENT OFFICE.

HUGH M. ROSS, OF WOODHAVEN, NEW YORK, ASSIGNOR TO ADRIANCE MACHINE WORKS, INC., OF BROOKLYN, NEW YORK, A CORPORATION OF NEW YORK.

BOTTLE-FILLING MACHINE.

Application filed September 28, 1923. Serial No. 665,259.

My invention relates to bottle filling and capping machines. The principal object of the invention is to provide in such machines improved means for controlling the escape 5 of the gas evicted from the bottle or container during the filling thereof; so that when the bottle or container is filled under pressure, as with carbonated liquid, loss of pressure under which the liquid is to be 10 stored in the bottle is avoided.

Other objects, features and advantages will appear more fully in the following detailed description and appended claims.

The accompanying drawings forming part 15 of this specification illustrate one embodiment of the invention.

In the drawings,

Fig. 1 is a vertical sectional view taken on line 1—1 of Fig. 2 of the filling and capping 20 head of a bottle filling machine; and

Fig. 2 is a section taken on line 2—2 of Fig. 1.

In the type of machine shown the bottle is mounted on a suitable table or support (not 25 shown) and the filling head 1 is movable downwardly into operative relation to the bottle 2. Suitable mechanism for supporting the bottle and producing the necessary 30 movement of the head is shown in United States Letters Patent to Calleson Reissue No. 14,657, dated June 10, 1919.

Mounted in extension 3 of the body of the head is a hollow or tubular liquid supplying plunger comprising a main or upper portion 4 and an extension 5 secured to the lower end of the portion 4. The extension 5 has secured therein a screw 6 having a central core 7 so as to provide an annular spiral liquid passage within the extension 40 5. A valve 8 within the plunger body 4 contacts with the valve seat 9 secured within the plunger. The valve 8 is movable axially within the plunger into or out of engagement with the seat 9 so as to be able to cut off or permit the flow of liquid through the plunger. The head 1 also has secured therein an elastic gasket 10 of rubber or other suitable material which is adapted to form a seal about the mouth of the bottle or other container. When the bottle is in filling 45 relation with respect to the head, the plunger extension 5 rests upon the top of the bottle neck as shown in Fig. 1. The lower end of the plunger extension is, as shown, provided

with an elastic insert 11 adapted to engage the 55 bottle and insure a seal between the mouth of the bottle and the fluid plunger. The head, as shown, also contains a suitable sealing throat 12 by which the skirts of a suitable cap may be forced around the rim on the 60 mouth of a bottle to seal the cap in place. This sealing throat may be of any suitable construction, for example, as shown in my United States Letters Patent No. 1,445,717, 65 dated Feb. 20, 1923. Suitable mechanism for moving the parts of the head such as the liquid plunger, the valve 8 and also the head itself are shown in reissue patent to Calleson No. 14,657 hereinbefore referred to. The mechanism described in the foregoing 70 detailed description is not per se new in my present invention, being disclosed in the patents hereinbefore referred to.

Referring now to the means for permitting 75 and controlling the escape of gas from the bottle or other container during the filling thereof, the screw 6 has secured axially thereto in the lower end thereof a cup 14 which has a flared open lower end. The upper end of the cup has a central perforation 15 leading to a passage 16 extending axially of the screw end of the water plunger, the passage 16 communicating with a transverse passage 17 extending through the screw 6 and the extension 5 to a circumferential 80 groove 18 extending around the extension 5. The groove 18 communicates through the space between extension 5 and the throat 12 and through the cap or closure chamber 19 and passage 19' with a chamber in which 85 there is mounted a vertical foraminous foam retarding member 20 the interior of which communicates through a passage 21 with a horizontal passage 22 leading to the passage 23 in which valve 24 is movable. The passage 23 comprises inner and outer portions, the outer portion being of larger diameter than the inner portion. The valve 24 has an outer end portion 25 fitting slidably in the larger portion of the passage 23 and 90 also an inner end portion 26 fitting slidably in the inner end of the passage 23 and normally pressed against the plunger extension 5 by a spring 27. The portion of the valve 24 between the parts 25 and 26 is of slightly 95 less diameter than the corresponding portions of the passage 23; so that, when the valve is open, communication is established 100 105

from the passage 22 through the passage 23 to a passage 28 leading to needle valve 29 which is adjusted to allow a fine opening to the atmosphere. The passages 22 and 28 are located on opposite sides of the shoulder 30 formed between the portions of the passage 23 of different diameter; so that, when the shoulder on the adjacent portion of the valve bears against this shoulder 30 in the passage 23, the valve will be closed and the escape of gas through the passage 28 and the port controlled by the valve 29 will be prevented. The groove 18 in the extension 5 of the liquid supply plunger is so arranged that when the plunger is in operative relation to the bottle the said valve stem, as shown, bears against the plunger above the groove and very close to it. When, however, the plunger is elevated with respect to the head from this position, the groove is so positioned as to receive the end of the valve stem and thereby permit closing of the valve 24.

In operation, the filling head having been brought into operative relation to the bottle, as shown in Fig. 1, and the liquid valve 8 having been opened, the liquid, such as carbonated water, is fed in an annular vortex into the bottle. The only escape for the gas (which is mainly air but may include some gas given off by the entering liquid) is the venting means including the cup 14, perforation 15, passages 16 and 17, groove 18, chamber 19, passage 19', capsule 20, passage 21, passage 23, passage 28 and the port controlled by the needle valve 29. As the plunger 4, during the filling operation, is in lowered position with respect to the head, the valve 24 will be held back into open position against the action of the spring 27; and the necessary venting of the gas will take place.

After the bottle has been filled, the plunger 4, 5 is elevated from the bottle (by means such as shown in Reissue Patent No. 14,657 mentioned above). This permits the valve stem 26 to enter the groove 18, allowing the spring 27 to automatically effect the closing of the valve 24. The head is now completely sealed and escape of gas from the bottle or from the interior of the head is effectively prevented and the desired pressure maintained in the head and container. Liquid valve 8 closes a short interval after the closing of the vent valve, shutting off the supply of liquid through the plunger, thus completing the filling operation and permitting the sealing of the bottle as described, for example, in the above-named reissue patent. When the liquid supply plunger is again lowered with respect to the head the groove 18 moves down below the valve stem 26 and the latter is automatically forced by the plunger back into open position as the inclined or cam-like upper wall of the groove

18 moves downwardly with respect thereto. The valve is thereupon held open by the plunger against the action of the spring 27.

It is to be understood that many modifications and changes may be made in the construction shown without departing from the spirit of my invention and the scope of the appended claims.

Having thus described my invention, what I claim as new and desire to secure by Letters Patent of the United States is:—

1. The combination of a vertically movable filling and capping head, a liquid supplying member mounted in said head and movable relative thereto, said head being provided with venting means permitting the escape of gas therefrom, and a valve coacting with said liquid supplying member and automatically operable upon the movement thereof for closing said venting means. 80

2. The combination of a filling and capping head adapted to coact with the mouth of a container to be filled and provided with adjustable venting means having an outlet directly and permanently open to the atmosphere and permitting the escape of gas from the head, a valve for closing said venting means, means tending to close said valve, and means including a plunger having a cam portion for opening said valve. 90

3. The combination of a filling and capping head adapted to coact with the mouth of a container to be filled and provided with venting means permitting the escape of gas from the head, a valve for closing said venting means, means tending to close said valve and means including a plunger movable into and out of sealing engagement with the container for opening said valve upon movement thereof into engagement with the container. 100

4. The combination of a head adapted to be moved vertically with respect to the mouth of a container to be filled and provided with venting means permitting the escape of gas from the head, a liquid supplying plunger mounted within said head and movable into and out of operative relation to the container, and a valve carried by said movable head for closing said venting means, said valve being operable by said plunger in its movements relatively to the head. 110

5. The combination of a vertically movable head adapted to coact with the mouth of a container to be filled and provided with venting means permitting the escape of gas from the head, a liquid supplying plunger movable vertically relatively to said head and having an axial gas passage forming part of said venting means and an annular liquid supplying passage surrounding said axial gas passage, and a valve for closing said venting means, said valve being operable by said plunger. 120

6. The combination of a filling and capping head adapted to coact with the mouth of a container to be filled, a liquid supplying plunger movable relatively to said head, a chamber within said head communicating with the said plunger and the outside atmosphere and provided with a foraminous foam retarder, and a valve operable to close communication between said chamber and the atmosphere, said valve being controlled by the said plunger.
- 5 In testimony whereof, I have signed my name to this specification.

HUGH M. ROSS.
